PANIC EXIT UNIT

Homer A. Eichacker, Indianapolis, Ind.

Application February 14, 1955, Serial No. 34,499

Term of patent 14 years

(Cl. D10—8)

Fig. 1 is a front elevational view of a panic exit unit embodying my new design, showing parts broken away for convenience of illustration;

Fig. 2 is a perspective view thereof taken from the upper right of Fig. 1 and drawn to a smaller scale; and

Fig. 3 is a similar perspective view thereof taken from the upper left of Fig. 1.

The dominant features of the design reside in the portions shown in solid lines.

I claim:

The ornamental design for a panic exit unit, as shown and described.
